Primary Examiner — John Windmuller(74) *Attorney, Agent, or Firm* — Schiff Hardin LLP(57) **CLAIM**

The ornamental design for a pole end clamp, as shown and described.

DESCRIPTION

FIG. 1 is a perspective view taken from the front, top, left side of the pole end clamp showing my new design;

FIG. 2 is a front elevational view thereof;

FIG. 3 is a rear elevational view thereof;

FIG. 4 is a left side elevational view thereof, the right side elevational view being a mirror image of the left side view;

FIG. 5 is a top plan view thereof; and,

FIG. 6 is a bottom plan view thereof.

Portions shown in broken lines are for illustrative purposes only and form no part of the claimed design.
